United States Patent Office

Des. 187,963

Patented May 17, 1960

187,963

HELICOPTER

Steven Postelson Apostolescu, New York, N.Y.

Application February 12, 1959, Serial No. 54,591

Term of patent 14 years

(Cl. D71—1)

FIG. 1

FIG. 2

FIG. 4

Fig. 1 is a side elevational view of a helicopter showing my new design.

Fig. 2 is a top plan view thereof.

Fig. 3 is a front elevational view thereof, with portions of the rotor blades broken away for convenience of illustration only.

Fig. 4 is a rear elevational view thereof.

The side of the helicopter not shown is a mirror image of the side shown in Fig. 1.

I claim:

The ornamental design for a helicopter, as shown and described.
